UNITED STATES PATENT OFFICE

HARRY D. CLOUD AND WILLIAM M. INGRAM, OF LEXINGTON, KENTUCKY

METAL AWNING

Application filed June 27, 1930. Serial No. 464,302.

This invention relates to new and useful improvements in metal awnings such as is shown and described in the patent to Cloud and Bitterman 1,615,214, January 25, 1927, and more particularly to a novel means for easily raising or lowering the awning sections.

In the accompanying drawings:

10 Figure 1 is a perspective view of a window casing showing the application of my invention thereto;

15 Figure 2 is a vertical section taken through the window casing and awning, the awning being shown in its extended or operative position;

Figure 3 is a similar view but showing the awning in its telescoped or inoperative position;

20 Figure 4 is a sectional view taken on the line 4—4 of Figure 2;

Figure 5 is a detail elevation showing the pivots of the awning sections;

25 Figure 6 is a detail sectional view showing the gearing for operating the awning sections;

Figure 7 is a sectional view taken on the line 7—7 of Figure 6;

30 Figure 8 is an enlarged detail elevation showing the connection between the combined pull and push link and the vertical and movable element;

Figure 9 is a sectional view taken on the line 9—9 of Figure 8;

35 Figure 10 is an enlarged detail elevation showing the mounting of the stationary pulley and the endless band associated therewith;

Figure 11 is a sectional view taken on the line 11—11 of Figure 10;

40 Figure 12 is a view in elevation showing the modified form of operating mechanism;

Figure 13 is a vertical sectional view taken on the line 13—13 of Figure 12;

45 Figure 14 is a vertical section taken on the line 14—14 of Figure 12;

Figure 15 is a horizontal sectional view taken on the line 15—15 of Figure 13; and

Figure 16 is a horizontal sectional view taken on the line 16—16 of Figure 14.

In the accompanying drawings, there is 50 shown a window casing A of ordinary construction which includes the usual sides 5—5a, a top 6, and a sill 7.

The awning is composed of a plurality of 55 metal sections a, b, c, d, and e, the section a being the lowermost section when the awning is in its operative or extended position, and the section e being the upper section, whereas the sections b, c, and d are intermediate sections. These sections are preferably 60 stamped from sheet metal, and all have a similar form. Each section includes spaced sides 8—8 which are substantially triangular in shape and a top 9 which is preferably rectangular in shape. The top section e is 65

rigidly attached to the window casing A and the forward edge of the section is provided with a down-turned lip 10. The next lower section d is provided with an upstanding lip 11 along its inner edge which is adapted to 70 engage the lip 10 and thereby limit the outward movement of said section d. This section d is pivotally connected as at 12 to the sides of the section e. The top 9 of the section c is provided along its forward edge 75 with a down-turned lip 13 and along its rear edge with an up-turned lip 14, the latter being engageable with the down-turned lip 15 extending along the forward edge of the section d. The section c is pivoted as at 16 to the sides of the section d. The section b is formed along the front edge of the top 9 with a downwardly extending lip 17 and along its rear edge with an upwardly extending lip 18, the latter being adapted to engage the downwardly extending lip 13 of the section c. The section b is pivotally connected as at 18a to the section d. The top 9 of the lowermost section a is provided along its rear edge with a forwardly extend-

80

85

90

95

ing lip 19 which is adapted to engage the lip 17 of the section *b*. The section *a* is pivoted as at 20 to the section *d*. The lowermost section *a* is also provided with a downwardly projecting flange which extends along the sides of the section *a* as at 21-21 and along its front as at 22. The pivots 12, 16, 18*a*, and 20 are disposed in a vertical line one above the other so as to permit the awning sections to be readily telescoped when moved upwardly to their inoperative positions, or to permit the sections to be readily extended to their operative positions. When thus extended the sections are held in their operative positions by means of the inter-engaging lips.

The above construction is substantially identical with that shown in the Cloud and Bitterman Patent 1,615,214 referred to above.

In order to positively raise and lower the awning sections, we have provided a manually operable mechanism which includes a vertically movable element mounted on the window casing, a combined pull and push link which is pivotally connected to the element and to the lowermost awning sections, and a means for imparting vertical movements to the element in order to raise and lower the sections. For this purpose we have provided an endless band *B* which is trained around a sprocket wheel 23 journaled on a shaft 24 which is fixed in a casing 25 secured to the outer face of the side 5 of the window casing and adjacent the sill 7. This endless band *B* extends upwardly from the sprocket wheel 23 in parallelism with the adjacent side 5 of the window casing, and is then trained over a pair of pulleys 26 and 27 mounted in a supporting frame 28, the latter being fixed to the top 6 of the window casing. The supporting frame 28 is located directly above the sprocket wheel 23. The endless band *B* then extends horizontally along the top 6 of the window casing and thence over pulleys 29 and 30 which are secured to a supporting frame 31 fixed to the top 6 of the window casing adjacent the other side 5*a* thereof. The right portion 32 of the endless band *B* thence extends downwardly along the adjacent side 5*a* of the window casing and is trained around a pulley 33 which is journaled on a supporting frame 34 fixed to the side face of the side 5*a* of the window casing. The endless band *B* is formed of two sections, one consisting of a length of wire 35 or other flexible means, and the other consisting of a sprocket chain 36. The wire connection 35 extends around the pulleys 26, 27, 29, 30, and 33, whereas the sprocket chain 36 extends around the sprocket wheel 23. Interposed in the wire connection 35 are connector elements 37, and carried by each element is an axle 38 on which is journaled a guide roller 39. Also journaled on each axle 38 is a combined pull and push link 40, the other end of the link being pivotally connected as at 41 to the flange 21 of the lower awning section *a*. The guide rollers 39 cooperate with vertically disposed guides 42 which are secured to the sides of the window casing.

Thus it will be seen that the endless band *B* is not only movable around fixed points, but one stretch of the band is movable vertically and carries the connector element 37 therewith. It will also be observed that, by means of the guides 42 and the cooperating guide rollers 39, the elements 37 will be guided in straight vertical lines and will be retained against bodily movements inwardly or outwardly relative to the window casing. Consequently, when the endless band *B* is moved, the connector elements 37 will be moved vertically and will carry with them inner pivotal ends of the combined push and pull links 40. Thus, when the connector elements 37 are moved upwardly the links 40 will positively swing the awning sections upwardly from an operative extended position to an inoperative closed position, and, when the connector elements 37 are moved downwardly, the links 40 will function to positively swing the awning sections downwardly and outwardly to their operative extended position.

In order to move the endless band *B* and thereby either raise or lower the awning, we have provided an operating shaft 43 and have journaled the same in the window casing. Fixed to the outer end of the shaft 43 is a gear 44 which meshes with a gear 45 fixed to the sprocket wheel shaft 24. The shaft 43 extends into the housing 25 and both gears 44 and 45 are enclosed within said housing. A crank handle 46 is fixed to the inner end of the operating shaft 43 and consequently, by rotating the handle, the endless band *B* will be moved and the awning raised or lowered, as above described.

The pulley 33 is journaled on a frame 33*a* which is vertically adjustable along the guide 42 by means of a screw 33*b* whereby the tension of the endless band may be varied.

It will be observed that both connector elements 37 and both links 40 are moved in unison, either upwardly or downwardly.

In the modified form shown in Figures 12 to 16 inclusive, I have mounted on the sides 5 of the window casing vertically disposed housings 47 and 48 respectively. Journaled in brackets 49-49 secured to the top 6 of the window casing is a shaft 50 having its ends projecting into the casings 47 and 48. Fixed to the ends of the shaft 50 and located within said housings are sprocket wheels 51 and 52 respectively. A sprocket chain 53 is trained around the sprocket wheel 51 and extends downwardly through openings 54-54 formed in the lower end of the casing 47, and the lower end of the sprocket chain is trained

around a sprocket wheel 55 which is fixed to a shaft 56 journaled in a casing 57 secured to the front face of the window casing. Trained around the sprocket wheel 52 is a sprocket chain 58, and this chain extends downwardly within the housing 48 and has its lower end trained around a sprocket wheel 59 which is journaled in the lower end of said housing. Attached to the respective sprocket chains 53 and 58 are bracket elements 60, and in each element is journaled an axle 61 similar to the axle 38 previously described, and to which one end of each link 40 is pivotally connected. Journaled on each axle 61 is a pair of guide rollers 62-62 which cooperate with a vertically disposed guide 63 mounted in the associated housing 47, or 48 as the case may be. Each of the housings 47 and 48 is U-shaped in cross section and is closed by a cover 64 which is formed with a vertically disposed slot 65 along which the axle 61 moves when the awning sections are moved upwardly or downwardly.

In order to exert either a positive upward pull on links 40 or a downward thrust thereon, we have provided an operating shaft 66 which is journaled in the window casing. Fixed to one end of the shaft 66 is a bevel gear 67 which meshes with a bevel gear 68 fixed on the shaft 56. A crank handle 69 is fixed to the inner end of the shaft 66, and consequently, when the shaft is rotated, both sprocket chains 53 and 58, together with the connecting cross shaft 50, will be operated. Consequently both elements 60 will be simultaneously raised or lowered and therefore both links 40 will be correspondingly moved.

In view of the above it will be apparent that we have provided a plurality of telescoping awning sections which are mounted to swing upwardly from an operative extended position to an inoperative closed position and vice versa. We have provided means for raising the sections, and this means includes a vertically movable element, a combined pull and push link which is pivotally connected to the element and to the lowermost awning section, and have provided means for imparting vertical movements to the element whereby a positive upward pull will be imparted to the link 40 or whereby a positive downward thrust will be imparted to the link so as to raise or lower the awning sections.

We claim:

1. In a window awning, a plurality of telescopic awning sections adapted to be mounted on a window casing to swing upwardly from an operative extended position to an inoperative closed position and vice versa, and means for raising the sections including vertically movable elements adapted to be respectively mounted on the sides of the window casing, a pair of combined push and pull links pivotally connecting the elements and the lowermost section, and means for simultaneously imparting vertical movements to said elements to raise and lower the sections.

2. In a window awning, a plurality of telescopic awning sections adapted to be mounted on a window casing to swing upwardly from an operative extended position to an inoperative closed position and vice versa, and means for raising the sections including vertically movable elements adapted to be respectively mounted on the sides of the window casing, a pair of combined push and pull links pivotally connecting the elements and the lowermost section, and means for simultaneously imparting vertical movements to said elements to raise and lower the sections.

2. In a window awning, a plurality of telescopic awning sections adapted to be mounted on a window casing to swing upwardly from an operative extended position to an inoperative closed position and vice versa, and means for raising the sections including vertically movable elements adapted to be respectively mounted on the sides of the window casing, a pair of combined push and pull links pivotally connecting the elements and the lowermost section, means adapted to be mounted on the sides of the window casing for respectively guiding said elements in straight vertical lines, and means for simultaneously imparting vertical movements to said elements to raise and lower the sections.

3. In a window awning, a plurality of telescopic awning sections adapted to be mounted on a window casing to swing upwardly from an operative extended position to an inoperative closed position and vice versa, and means for raising the sections including vertically movable elements adapted to be respectively mounted on the sides of the window casing, a pair of combined push and pull links pivotally connecting the elements and the lowermost section, means adapted to be mounted on the sides of the window casing for respectively guiding said elements in straight vertical lines comprising vertically disposed tracks and rollers respectively carried by the elements and engaging said tracks, and means for simultaneously imparting vertical movements to said elements to raise and lower the sections.

4. In a window awning, a plurality of telescopic awning sections adapted to be mounted on a window casing to swing upwardly from an operative extended position to an inoperative closed position and vice versa, and means for raising the sections including an endless band adapted to be mounted on the window casing and movable around spaced points, a combined pull and push link pivotally connecting the band and the lowermost section, and means for moving said band to raise and lower the sections.

5. In a window awning, a plurality of telescopic awning sections adapted to be mounted on a window casing to swing upwardly from an operative extended position to an inoperative closed position and vice versa, and means for raising the sections including an endless band adapted to be mounted on the window casing and movable around spaced points, a combined pull and push link pivotally connecting the band and the lowermost section, and means for moving said band to raise and lower the sections including a sprocket wheel connected to the band and a manually operable crank for rotating said wheel.

6. In a window awning, the combination with a plurality of telescoping awning sections mounted to swing upwardly from an operative extended position to an inoperative closed position and vice versa, and means for raising the sections including a vertically movable element, a combined pull and push link pivotally connecting the element and the lowermost section, and means for imparting vertical movements to said element to raise and lower the sections, the pivotal connection between the link and the element being located in a horizontal plane higher than the horizontal plane containing the pivotal connection between the link and the lowermost section when the awning is in its operative extended position. 70
- 10 7. In a window awning, a plurality of telescopic awning sections adapted to be mounted on a window casing to swing upwardly from an operative extended position to an inoperative closed position and vice versa, and means for raising the sections including an endless band adapted to be mounted on the 80 casing to extend along both sides and top thereof, a pair of combined push and pull links pivotally connecting the endless band at opposite sides of the window casing and the lowermost section, and means for moving said band whereby the links and the sections will be raised and lowered. 85
- 15 8. In a window awning, a plurality of telescopic awning sections adapted to be mounted on a window casing to swing upwardly from an operative extended position to an inoperative closed position and vice versa, and means for raising the sections including endless bands adapted to be respectively mounted on the opposite sides of the window 90 casing for movement about upper and lower fixed points, driving connections between the bands, connections between the lower section and the bands, and means connected to one of the bands for moving both bands in unison and for raising and lowering the sections. 95
- 20 9. In a window awning, a plurality of telescopic awning sections adapted to be mounted on a window casing to swing upwardly from an operative extended position to an inoperative closed position and vice versa, and means for raising the sections including a pair of upper and lower sprockets adapted to be journaled on each side of the window 100 casing, a cover surrounding each pair of sprockets and adapted to be secured to the window casing, an endless chain surrounding each pair of upper and lower sprockets, each cover being provided with a vertically disposed elongated slot, a vertically disposed 105 stationary guide mounted within each cover, a bearing element connected to each chain and disposed within the cover, an axle journaled in each bearing element and projecting outwardly through the slot of the cover, a roller mounted on each axle for engage- 110
